UNITED STATES PATENT OFFICE.

JEFFREY T. FERRES, OF LOS ANGELES, CALIFORNIA.

MACHINE FOR MAKING CORRUGATED PAPER-BOARD.

1,142,409.

Specification of Letters Patent:

Patented June 8, 1915.

Application filed November 19, 1912. Serial No. 732,288.

To all whom it may concern:

Be it known that I, JEFFREY T. FERRES, a citizen of the United States, residing at Los Angeles, in the county of Los Angeles, in the State of California, have invented certain new and useful Improvements in Machines for Making Corrugated Paper-Board, of which the following is a specification.

My invention relates to a machine for making what is commonly known as double faced corrugated paper board by applying a sheet of paper to a single faced corrugated paper board, and the object thereof is in general to provide a comparatively simple and efficient machine for producing an extremely strong and uniform quality of board of this character.

One object of my invention is to provide simple and efficient means for holding the lining sheet in contact with the adhesive onto the crowns of the corrugated sheet solidly and steadily as the paper passes through the machine without any possibility of kneading of the paper such as occurs when feed rolls are employed, such lining sheet being preferably heated in such a manner and by such means that all danger of scorching or burning the paper is avoided.

Another object of my invention is to provide efficient means whereby when the machine is stopped the corrugated sheet is automatically removed from contact with the adhesive applying roll thereby preventing the adhering of such sheet to the roll during the period of stoppage and the consequent tearing of the paper when the machine is again started.

Another object of my invention is to so construct the movable platforms or endless carriers and the bearings thereof that such platforms cannot become soiled by the lubricant used.

Other novel and advantageous features of construction and operation will be apparent from the description hereinafter given.

In the drawings Figure 1 is a side elevation of my machine with the central portion thereof broken away; Fig. 2 a section on the line 2-2 of Fig. 1 but on a larger scale; Fig. 3 a perspective view of the cutter; Fig. 4 a longitudinal sectional elevation of the machine illustrating the front end thereof; Fig. 5 a similar view illustrating the rear end of the machine, these two figures 4 and 5 when combined illustrating the entire machine;

Fig. 6 a longitudinal section of one of the rolls over which the lining or facing sheet passes and by which it is heated and Figs. 7 and 8 detail views of part of the cutting mechanism and of the lever 39 respectively. 60

Referring to the present embodiment of my invention as shown in the drawings, the machine is provided with front end frame 1 and rear end frame 2 and with any suitable number of standards 3 and cross bars 4 65 according to the length of the machine.

It will be understood that this machine may be of any length desired, the longer the machine the more rapidly it can be run inasmuch as longer time is given for the adhesive to dry. The end frames carry the working parts of the machine and the standards and cross bars in particular support the endless carriers or platforms hereinafter described. 70

In the front end frame 1 is journaled the two shafts 5 and 6 to which are secured respectively the sprocket wheels 7 and 8 of the upper and lower endless carriers or platforms. 75

On the rear end frame is journaled corresponding shafts 9 and 10 and sprocket wheels 11 and 12 with the exception that these sprocket wheels are the driving wheels for the endless carrier while the wheels 7 85 and 8 are merely idler sprocket wheels. These endless carriers or platforms are substantially similar in construction except that the lower platform is wider than the upper one. Referring to the uppermost carrier the same comprises the two side chains 13 and a series of lags 14 secured thereto. These lags extend transversely of the chains and of the machine and are of such size that the horizontal reaches of the same constitute a 90 substantially continuous platform or surface which on the lowermost reach is presented to the corrugated paper board passing through the machine. The other or lowermost endless carrier or platform is similarly 100 composed of endless side chains 15 and the series of lags 16. As hereinbefore suggested the machine and consequently the endless carriers may be of any desired length. These carriers or platforms may be driven in any 105 suitable manner and in the present instance the driving mechanism comprises the driving pulley 17 preferably driven by an electric motor (not shown), and secured to the shaft 9. As shown in Fig. 5 this shaft car- 110

ries a gear 81 which through the medium of the train of the same sized gears 18, 18, drives a gear 19 secured to the shaft 10, with the result that both shafts 9 and 10 and consequently the carriers are driven at the same speed.

In connection with these endless carriers or platforms there is provided a series of rollers bearing endless chains indicated at 20, 21 and 22. The first mentioned endless chain co-operates with the uppermost endless carrier composed of the chains 13 and lags 14 and runs loosely over the idler wheels 23 on shafts 24 suitably mounted in the end frames 1 and 2. The chains 20 on their upper reach are supported by stationary tracks 25 which in turn are supported by the cross bars 4 of the machine. As clearly shown in Fig. 2 these chains are positioned along the longitudinal sides of the machine, and co-operate with the tracks 14^a on the intermediate portion of the lags 14. As shown these chains are of the roller type, the side pieces of each link being wider than the diameter of the rollers. In a plane above the lower reaches of the chains 20 and the lags 14 pressure shoes 26 are provided the same being arranged longitudinally of the machine and in a position to press the chains 20 downwardly upon the lags 14. These shoes may be made vertically adjustable in suitable manner so that any pressure can be put upon the paper. In the present instance I provide for this purpose the vertical adjusting screws 27 co-operating with the supports 25 and the shoes 26.

The endless chains 21 are also of the roller type described and are supported on their upper reach by means of the longitudinal supports 28, these chains co-operating with the tracks 16^a of the lowermost endless platform or carrier comprising the chains 15 and lags 16, the upper reach of such chains 21 supporting the lags 16 on their upper reach. These chains 21 extend at their ends over the idlers 29 on the shafts 30 mounted in the end frames 1 and 2.

The third set of chains 22 are also of the roller type the same passing over the idler rolls 31 on the shaft 32 mounted in the end frames 1 and 2. Such chains also have the supports 33 similar to the supports 25 and 28 and in addition have a bottom support 34 for supporting the lower reach of the chains. However, these chains 22, unlike chains 20 and 21 co-operate with the ends of the lags, and moreover, the lags 16 which they contact are formed therat in the peculiar manner indicated in Fig. 2 wherein it is seen that transverse recesses 16^b are cut in the lags to accommodate the side pieces of the links leaving a track portion 16^c for the rollers to contact with. Furthermore, these lags 16 are extended at their ends beyond the ends of the lags 14 so that the points of

contact of chains 22 are entered beyond the working surface of the lags 16, thereby avoiding smearing thereof by lubricant from the chains.

At the front of the machine and upon the end frames 1 is removably mounted the pan 35 adapted to contain the adhesive such as silicate or paste. Within the adhesive there dips the adhesive applying roll 36 journaled at its ends in the frames 1 and adapted to apply the adhesive to the crowns of the single faced corrugated board indicated at A.

Upon a transverse shaft 37 whose ends are journaled in the end frames 1 are mounted two vertical levers 38 and 39, both of them being arranged outside of the frames 1. These levers are keyed to the shaft 37 so that manipulation of the lever 39 will cause a corresponding movement of the other lever. These levers are similar with the exception that the lever 39 is provided with a dog 40 adapted to co-operate with an adjustable plate 41 forming an adjustable stop for these levers. This plate is adjustable by means of the adjusting screw 42 co-operating with a lug 43 forming a part of the end frame.

Upon the shaft 37 is arranged an idler roller 44 over which the corrugated paper board A passes. These levers carry a horizontal shaft 45 which is adjustable inside supporting levers by means of the adjusting screws 46. In addition these levers carry an idler roller 47 which revolves on the shaft 45 and over which the paper board A passes and by which it is presented to the roll 36 whereby the adhesive is applied to the crowns of the corrugations. In addition the levers 38 and 39 carry between them a scraper 48 adapted to co-operate with the roll 36 at a point below the point of application of the adhesive, the said roll 36 rotating in an anti-clockwise direction (Fig. 4).

The roll 36 is driven in suitable manner as by means of the sprocket chain 49 and the sprocket wheels 50 and 51, the former being secured to the shaft 5 and the latter to the shaft 36^a of the roll 36. The construction and arrangement is such that the surface speed of the roll 36 is the same as the speed of the lags and consequently of the paper board A presented to the roll 36.

Movement of either one of the levers 38 and 39 is designed to stop the machine and to automatically withdraw the board A from the adhesive roll. To this end the lever 39 has attached to it a rod 39^a which runs to a switch (not shown) of an electric motor which is preferably employed as the prime mover. When the lever is thrown rearwardly the switch is operated by the rod 39^a to shut off the current to the motor and at the same time the board A is withdrawn from the roll. Also, by the same act the scraper 48 is withdrawn from the roll with

the result that the adhesive on such roll above the scraper can run back into the pan. As clearly shown in Fig. 4 this pan is of such construction that it may be readily removed for cleansing purposes without disturbing any other part of the machine.

The lining or facing strip B which is to be applied to the single faced corrugated board A is supplied from a roll 52 mounted 10 in brackets 53 secured to the top of the end frame 1. The sheet B passes over the two idler rollers 54 and 55 and thence in a substantially horizontal direction to a plane between the lags 14 and 16 where such sheet 15 is applied to the crowns of the corrugations of the single faced corrugated board and held in contact therewith by means of the pressure applied by these lags or endless platforms until the adhesive becomes set. 20 By preference the idler rollers 54 and 55 are heating rollers whereby the sheet B is heated preliminary to its application to the board A. These rollers are similarly heated by a suitable heating fluid and in order 25 to prevent scorching of and injury to the paper particularly when the machine is stopped, I prefer to heat them by water which is heated and kept heated by means of steam. As shown in the detail view in 30 Fig. 6, the roller 54 is hollow and supplied with water. Entering the gudgeon 54a of one of the ends of the roller is a steam supply pipe 56 whose inner end is bent laterally so as to always be immersed in the 35 water. The other gudgeon of the roller is likewise hollow and provided with an overflow pipe 57 which takes care of any overflow occurring, particularly when the water within the roller 54 is being heated. It 40 will be understood that the other roller 55 is of similar construction.

The machine is continuous in its operation so long as the corrugated board A and the facing sheet B are supplied thereto and consequently the double faced corrugated board produced would be continuous but in practice it is desirable or necessary to cut this board product with accuracy in predetermined lengths. In the present instance I have provided a simple and efficient cutting mechanism for this purpose. This cutting mechanism is mounted in the end frame 2 and as shown in Figs. 1, 3 and 5 the roll 58, preferably of hardened steel or chilled cast iron is mounted horizontally in such end frame and adjusted vertically in suitable manner as by means of the adjusting screws 59 coöperating with the journal boxes 60 for said roll, these journal boxes being movable in vertical slots 61 in the end frame 2. The lowermost point of this roll 58 is in the plane of the facing sheet B which was applied to the single faced corrugated board, that is in the plane of the top surface of the board product of the machine. 65

Journalized below the roll 58 is another roll 62 which carries in its periphery a series of radially disposed knives 63 extending the length of such roll and projecting therefrom a distance sufficient to cut through the 70 board product in coöperation with the under surface of the roll 58. In the present instance, these knives 63 are two in number, but one or more may be used. For the severing of the paper the roll 62 is automatically given a half turn when two knives are used or a full turn when one is used by the means illustrated in Figs. 1 and 7. As shown in Fig. 7 the shaft 64 of roll 62 carries a sprocket wheel 65 over which extends 80 a sprocket chain 66 which also passes over a sprocket wheel 67 on the horizontal movable stud 68. The chain 66 is provided with detachable links, all of the links being ordinary plain links except those provided 85 with lugs 69. These lugs are adapted to engage the peripheral shoulders or projections 70 of a disk 71 secured to the shaft 64. Each lug 69 is therefore adapted to engage the disk 71 in clockwise direction (Fig. 5) 90 thereby rotating the cutter roll 62 a half turn or a full turn if two lugs are used near together. The sprocket wheel 65 is driven by the gear 72 secured thereto by bolts 73 and driven in suitable manner as by means 95 of the idler gear 74 driven by the gear secured to shaft 10.

In order to prevent any possibility of overthrow of the roll 62, I key to its shaft a brake drum 77, Fig. 5, and provide a co-operating brake band 78 to which is fastened a weight 79. This brake band is connected at one end to said weight and at the other end to a fixed point 80 on the end frame. Where only one knife is used in roll 62 105 additional lugs are used on chain 66 to give it one complete turn.

Suitable driving mechanism may be employed for the cutter roll 58 and in the present instance such mechanism comprises a gear 81 secured to the drive shaft 9, pinion 82 journaled in the end frame 2 and the gear 83 secured to the shaft 84 of said cutter roll 58. It will be understood that the cutters are timed to move at a predetermined moment and at the same speed as the paper product with the result that the board lengths are cut uniformly, rapidly and without checking the feed of the board or causing it to buckle in front of the cutters. The board lengths may be varied by the relative position of the lugs 69 in the chain 66. By preference sheet iron guards 85 are placed in advance of the cutting rolls to prevent wads of paper or the operator from being caught between such rolls. It will be understood that the knives in the cutter head cut against the hardened surface of roll 58 and sever the paper by pressure. 110 115 120 125 130

I claim:

1. In a machine of the class described, the combination of two endless carriers, forming, by means of two adjoining reaches, platforms or beds between which the paper board is held and carried through the machine, said carriers being provided with tracks on one side, and endless roller chains coöperating with said tracks to support the carriers. 5
10. 2. In a machine of the class described, the combination of two endless carriers and transverse lags forming, by means of two adjoining reaches, platforms or beds between which the paper board is held and carried through the machine, and endless chains arranged between the upper and lower reaches of the lags of the two endless carriers and coöperating therewith to support them. 15
15. 3. In a machine of the class described, the combination of two endless carriers and transverse lags forming, by means of two adjoining reaches, platforms or beds between which the paper board is held and carried through the machine, endless chains arranged between the upper and lower reaches of the lags of the two endless carriers and coöperating therewith to support them, and a third endless roller chain arranged below and coöperating with the lower reach of the lowermost endless carrier. 20
20. 4. In a machine of the class described, the combination of two endless carriers and transverse lags forming, by means of two adjoining reaches, platforms or beds between which the paper board is held and carried through the machine, and endless roller chains coöperating directly with said lags to support said platforms, said chains being arranged in pairs. 25
25. 5. In a machine of the class described, the combination of two endless carriers and transverse lags forming, by means of two adjoining reaches, platforms or beds between which the paper board is held and carried through the machine, and endless chains coöperating directly with said lags to support said platforms, said chains being arranged in pairs and being driven by contact with the platforms. 30
30. 6. In a machine of the class described, the combination of two endless carriers and transverse lags forming, by means of two adjoining reaches, platforms or beds between which the paper board is held and carried through the machine, and endless chains coöperating directly with said lags to support said platforms, said chains being of the roller type and driven by contact with the platforms. 35
35. 7. In a machine of the class described, the combination of two endless carriers forming, by means of two adjoining reaches, platforms or beds between which the paper
- board is held and carried through the machine, and endless chains coöperating to support said platforms, said platforms having tracks with which said chains coöperate. 40
40. 8. In a machine of the class described, the combination of two endless carriers coöperating to form two traveling platforms or beds between which the paper board is held and carried through the machine, each carrier comprising endless chains and transverse legs secured thereto, and provided with tracks, and endless chains each of which is positioned within the reaches of its carrier to support and hold them in position and with which said tracks coöperate. 45
45. 9. In a machine of the class described, the combination of two endless carriers forming, by means of two adjoining reaches, platforms or beds between which the paper board is held and carried through the machine, endless chains positioned within the reaches of the carriers for supporting and holding them in position, and a third endless chain positioned below the lower reach of the lowermost carrier for supporting the same. 50
50. 10. In a machine of the class described, the combination of two endless carriers, forming, by means of two adjoining reaches, platforms or beds between which the paper board is held and carried through the machine, said carriers being provided with tracks on one side, endless roller chains coöperating with said tracks to support the carriers, and stationary supports for the upper reaches of the chains, the lower reaches thereof resting upon the tracks of the adjacent carriers. 55
55. 11. In a machine of the class described, the combination of two endless carriers forming, by means of two adjoining reaches, platforms or beds between which the paper board is held and carried through the machine, endless roller chains positioned within the reaches of the carriers for supporting them, stationary supports for the upper reaches of the chains, the lower reaches thereof resting upon the corresponding reaches of the carriers, and adjustable shoes pressing the chain coöperating with the uppermost carrier upon the lower reach of the latter. 60
60. 12. In a machine of the class described, the combination of two endless carriers forming, by means of two adjoining reaches, platforms or beds between which the paper board is held and carried through the machine, endless roller chains positioned within the reaches of the carriers for supporting them, stationary supports for the upper reaches of the chains, the lower reaches thereof resting upon the corresponding reaches of the carriers, and adjustable shoes pressing the chain coöperating with the uppermost carrier upon the lower reach of the latter. 65

latter, said shoes being supported from its said stationary support above it.

13. In a machine of the class described, the combination of two endless carriers forming, 5 by means of two adjoining reaches, platforms or beds between which the paper board is held and carried through the machine, stationary tracks 25 arranged below the upper reach of the uppermost carrier, 10 and an endless chain traveling on said track and between it and such upper reach and in contact with the latter.

14. In a machine of the class described, the combination of two endless carriers forming, 15 by means of two adjoining reaches, platforms or beds between which the paper board is held and carried through the machine, a depending shoe 26 in proximity with the lower reach of the uppermost carrier, 20 and an endless chain traveling between such shoe and such lower reach and adapted to hold the latter upon the board.

15. In a machine of the class described, the combination of two endless carriers forming, 25 by means of two adjoining reaches, platforms or beds between which the paper board is held and carried through the machine, a depending shoe 26 in proximity with the lower reach of the uppermost carrier, 30 and an endless chain traveling between such shoe and such lower reach and adapted to hold the latter upon the board, said shoe being vertically adjustable.

16. In a machine of the class described, 35 the combination of two endless carriers forming, by means of two adjoining reaches, platforms or beds between which the paper board is held and carried through the machine, a depending shoe 26 in proximity with the lower reach of the uppermost carrier, 40 and an endless chain traveling between such shoe and such lower reach and adapted to hold the latter upon the board, said shoe having supporting adjusting screws by 45 which it is vertically adjustable.

17. In a machine of the class described, the combination of two endless carriers co-operating to form two traveling platforms or beds between which the paper board is 50 held and carried through the machine, each carrier comprising endless chains and transverse lags secured thereto, two endless chains each of which is positioned within the reaches of its carrier, and a third endless chain co-operating with the lags of the 55 lower reach of the lowermost carrier.

18. In a machine of the class described, the combination of two endless carriers co-operating to form two traveling platforms or beds between which the paper board is 60 held and carried through the machine, each carrier comprising endless chains and transverse lags secured thereto, the lags of the uppermost carrier being provided with 65 tracks on one side and the lags of the other

carrier being provided with tracks on both sides, two endless chains each of which is positioned within the reaches of its carrier and with which the tracks of the uppermost carrier and one set of tracks of the other carrier co-operate, and an endless chain co-operating with the remaining set of tracks of said other carrier.

19. In a machine of the class described, the combination of two endless carriers co-operating to form two traveling platforms or beds between which the paper board is held and carried through the machine, each carrier comprising endless chains and transverse lags secured thereto, the lags of the 70 lowermost carrier being extended at their ends beyond the ends of the lags of the uppermost carrier, and endless supports co-operating with said extended ends of the lags.

20. In a machine of the class described, the combination of two endless carriers co-operating to form two traveling platforms or beds between which the paper board is held and carried through the machine, each 90 carrier comprising endless chains and transverse lags secured thereto, the lags of the lowermost carrier being extended at their ends beyond the ends of the lags of the uppermost carrier, and endless roller chains co-operating with said extended ends of the lags.

21. In a machine of the class described, the combination of two endless carriers co-operating to form two traveling platforms or beds between which the paper board is held and carried through the machine, each carrier comprising endless chains and transverse lags secured thereto, the lags of the lowermost carrier being extended at their 105 ends beyond the ends of the lags of the uppermost carrier, and being provided thereat with tracks, and endless roller chains co-operating with said tracks.

22. In a machine of the class described, the combination of two endless carriers co-operating to form two traveling platforms or beds between which the paper board is held and carried through the machine, each carrier comprising endless chains and transverse lags secured thereto, pairs of endless chains, each pair positioned within the reaches of its carrier, and another pair of endless chains co-operating with the lower reach of the lowermost carrier.

23. In a machine of the class described, the combination of two endless carriers co-operating to form two traveling platforms or beds between which the paper board is held and carried through the machine, each 115 carrier comprising endless chains and transverse lags secured thereto, the lags of the lowermost carrier being extended at their ends beyond the ends of the lags of the uppermost carrier, and being provided thereat 120

6
with tracks, said tracks being separated from the board holding surface of the lags by a depression, and endless chains coöperating with said tracks.

- 5 24. In a machine of the class described, the combination, of two endless platforms or beds between which the paper board is held and carried through the machine, endless roller chains arranged between the upper and lower reaches of the two endless platforms and coöperating therewith to support them and a third endless roller chain arranged below and coöperating with the lower reach of the lowermost endless plat-

form and at the end thereof outside the surface over which the paper passes.

25. In a machine of the class described, the combination of a power driven adhesive applying roll, rolls over which the lining sheet passes and two endless roller bearing 20 platforms between which the paper is carried, the lower platform being wider than the corrugated paper made.

JEFFREY T. FERRES.
